UNITED STATES PATENT OFFICE.

THOMAS B. FARRINGTON, OF CHICAGO, ILLINOIS.

UNDER-GARMENT.

SPECIFICATION forming part of Letters Patent No. 228,748, dated June 15, 1880.

Application filed September 30, 1879.

To all whom it may concern :

Be it known that I, THOMAS B. FARRINGTON, of Chicago, in the county of Cook and State of Illinois, have invented certain new and useful Improvements in Under-Garments; and I do hereby declare that the following is a full, clear, and exact description thereof, reference being had to the accompanying drawings, and to the letters of reference marked thereon, which form a part of this specification.

This invention relates to the combination, with a woven or cloth under-garment, of knitted wrist or ankle pieces or tips of that character adapted, by their elasticity, to hug the wrist or ankle.

I am aware that woven garments have been heretofore provided with knitted tips, and do not claim, broadly, such combination; but my invention consists in a cloth body and knit tip, divided at its edge to receive the edge of the cloth.

In the drawings, Figure 1 shows the extremity of a sleeve or leg provided with the knitted wrist or ankle piece. Fig. 2 is an enlarged section of the same; and Fig. 3 is a transverse section, more clearly showing the mode of joining the two parts of unlike fabric.

A represents the body of the garment, made, say, of closely-woven flannel, and being, therefore, comparatively inelastic.

B represents the wrist or ankle part, which

is made, by the usual method of knitting such part, to have a special tendency to contract about the wrist or ankle. For the purpose of uniting the two parts the upper margin of the tip B is longitudinally divided in making it, so as to have a longitudinal slit in its edge, into which the less elastic edge of the part A may be inserted; as shown in Fig. 1. In securing the parts to each other the part B is stretched to equal the length of the edge of A, and the whole is stitched through and through, or each edge of the divided portions c and d may be separately secured by felling to the body A. If desired to give still better finish the added strip e may be applied to cover the upper edge of the knitted tip on the outer side, as shown in Figs. 1 and 3.

Having thus described my invention, I claim—

In combination with the cloth body A, the knit tip B, divided at its upper edge to receive the edge of the body, substantially as shown and described.

In testimony that I claim the foregoing as my invention I affix my signature in presence of two witnesses.

THOMAS B. FARRINGTON.
